US0D1057662S

(12) **United States Design Patent** (10) **Patent No.:** **US D1,057,662 S**
(45) **Date of Patent:** **** Jan. 14, 2025**

(54) **POWER STRIP**

(71) Applicants: **VIRIDI E-MOBILITY**

TECHNOLOGY (NINGBO) CO., LTD., Ningbo (CN); **ZHEJIANG ZEEKR INTELLIGENT TECHNOLOGY CO., LTD.**, Ningbo (CN); **ZHEJIANG GEELY HOLDING GROUP CO., LTD.**, Hangzhou (CN)

(72) Inventors: **Ye Yuan**, Zhejiang (CN); **Jia Li**, Zhejiang (CN); **Zequn Yu**, Zhejiang (CN); **Songlin Yang**, Zhejiang (CN); **Yue Ma**, Zhejiang (CN)

(**) Term: **15 Years**

(21) Appl. No.: **35/518,497**

(22) Filed: **Aug. 22, 2023**

(80) **Hague Agreement Data**

Int. Filing Date: **Aug. 22, 2023**

Int. Reg. No.: **DM/231683**

Int. Reg. Date: **Aug. 22, 2023**

Int. Reg. Pub. Date: **Sep. 29, 2023**

(51) **LOC (15) Cl.** **13-03**

(52) **U.S. Cl.**

USPC **D13/139.8**; D13/137.2

(58) **Field of Classification Search**

USPC D13/103, 108, 110, 137.1–137.2, D13/139.6–139.8, 146, 152

CPC G06F 3/0219; H01R 24/22

See application file for complete search history.

Primary Examiner — Sandra Snapp

Assistant Examiner — Bryan N. Melvin

(57) **CLAIM**

The ornamental design for a power strip as shown and described.

DESCRIPTION

1.1: Perspective view;

1.2: Front view;

1.3: Back view;

1.4: Left view;

1.5: Right view;

1.6: Top view;

1.7: Bottom view;

1.8: Perspective view; and

1.9: Enlarged view of portion labeled “1.9” in 1.1.

The dash-dash broken lines in the drawings depict the portions of the power strip that form no part of the claimed design.

The dot-dash broken lines in the drawings depict the boundaries of the enlarged views and form no part of the claimed design.

The label 1.9 in reproduction 1.1 forms no part of the claimed design.

1 Claim, 9 Drawing Sheets
